SEPARATION OF C-9-ALKARYL HYDROCARBONS BY AZEOTROPIC DISTILLATION

Art C. McKinnis, Long Beach, Calif., assignor to Union Oil Company of California, Los Angeles, Calif., a corporation of California

Application November 16, 1953, Serial No. 392,129

3 Claims. (Cl. 202—42)

This invention relates to methods for separating aromatic hydrocarbons boiling above about 150° C. from other hydrocarbons boiling in the same range, e. g. paraffins or naphthenes. Broadly stated the method consists in azeotropically distilling the mixture to be separated with nitromethane as the azeotrope former. It is found that nitromethane is capable of forming low-boiling azeotropes with paraffins and naphthenes boiling between about 150° and 220° C., and that the aromatic hydrocarbons boiling in that range do not form azeotropes with nitromethane. Olefinic hydrocarbons in this boiling range may exhibit slight azeotropy with nitromethane, but generally such azeotropes are higher boiling than the paraffin or naphthene azeotropes and may hence be separated therefrom.

The invention is particularly concerned with the alkaryl hydrocarbons boiling approximately in the 160—170° C. range, which includes most of the following C-9 alkaryl hydrocarbons:

Name of compound:	Boiling point
Hemimellitene	176.1
Pseudocumene	169.3
Mesitylene	164.7
o-Ethyl toluene	162.0
m-Ethyl toluene	162.5
p-Ethyl toluene	162.0
Cumene	152.4
Propyl benzene	159.2

Certain of these materials have become increasingly important as raw materials for the synthesis of various chemicals such as terephthalic acid, toluic acid, phthalic anhydride, and similar materials. A particularly rich source material for such hydrocarbons consists of the gasoline fractions obtained from modern reforming of hydroforming operations wherein cracked or straight-run gasoline is subjected to catalytic hydroforming to increase the aromaticity and improve the octane rating and general stability of the gasoline. The naphthene components in the raw gasoline are largely dehydrogenated to form the corresponding aromatic hydrocarbons. Substantial isomerization and cyclization also may take place. Olefins which may have been present in the original gasoline are largely hydrogenated during reforming to form paraffins and naphthenes.

When such reformed gasolines are subjected to distillation a narrow heart-cut boiling between about 160° and 170° C. may be obtained which will ordinarily be more than 50% aromatics, the remainder being mostly paraffins and naphthenes. The separation of the aromatics from the nonaromatics in the 160—170° C. fraction presents considerable difficulties. Solvent extraction is inherently inefficient because the solvents ordinarily employed are selective for the aromatics which make up the predominant part of the cut. Solvent extraction therefore requires large volumes of solvent and entails considerable handling expense and heat losses. Several materials are known to form azeotropes selectively with paraffin hydro-

carbons in preference to aromatic hydrocarbons, but the common azeotrope formers are found to be subject to several disadvantages when they are employed for azeotroping high-boiling paraffins. For example the aliphatic acids, alcohols, Cellosolves, nitriles, pyridine and acetylacetone are found either to form azeotropes with pseudocumene, or the paraffin azeotrope taken overhead contains only a small percent of hydrocarbons. The present invention is based upon my discovery that nitromethane is an exceptionally effective azeotroping agent for separating high boiling paraffins, i. e. those boiling at 150° C. or above, from other hydrocarbons in the same boiling range.

It is therefore an object of this invention to provide economical methods for separating C-9 alkaryl hydrocarbons, or other aromatics boiling in the same or higher ranges from like-boiling paraffin and naphthene hydrocarbons. A further object of the invention is to provide economical means for separating any desired group of high-boiling aromatic hydrocarbons from reformed gasoline fractions. A specific object is to provide effective means for removing the C-9 alkaryl hydrocarbons from such reformates in substantially 100% purity. Other objects of the invention will be apparent from the more detailed description which follows.

It is known in the art (Geckler et al., U. S. Patent No. 2,316,126) that toluene (B. P. 110.6° C.) may be separated from like-boiling paraffins by azeotroping the paraffins overhead with nitromethane. The azeotropic overhead contains about 45% nitromethane and 55% paraffin hydrocarbons. Toluene also azeotropes, but at a higher temperature. The behavior of nitromethane as an azeotroping agent for paraffins has also been explored in connection with paraffins boiling up to 128° C. The n-octane azeotrope with nitromethane contains about 53% nitromethane (Lecat, Tables Azeotropiques, 2nd edition, 1949, page 311). Theoretically therefore, nitromethane would be expected to be uneconomical as an azeotrope former for high boiling paraffins, since it would be necessary to volatilize large quantities of nitromethane per volume of hydrocarbon. It has been unexpectedly discovered however that when a 160—170° C. heart-cut of catalytically reformed naphtha is azeotroped with nitromethane, the azeotrope formed is much richer in hydrocarbons than would be expected.

It is well known in azeotropy that there is a definite relationship between the absolute difference in boiling points of the azeotrope components, $|\Delta|$, and the difference in boiling points between the azeotrope and the lower boiling component thereof, δ . Lecat [Compt. rend. 183,880 (1926)] has in fact set up a mathematical relationship between these factors as follows:

$$\delta = a + |\Delta|b + \Delta^2c$$

55 where:

Δ = (boiling point of component A) (boiling point of component B),

$|\Delta|$ = difference in boiling point of A and B (absolute value of Δ),

60 δ = difference in boiling point of azeotrope and the lower boiling component,

$a, b, \dots, c$ = constants for a given series of related azeotropes such as methanol-hydrocarbons.

65 In the case of nitromethane azeotropes with paraffins the relationship of $|\Delta|$ with δ is set forth in Figure I, curve B. It will be noted that n-heptane, n-octane, n-hexane and cyclopentane all lie on essentially the same continuous curve. As δ for the curve approaches zero, the likelihood of any appreciable azeotrope formation becomes less and less. At $\delta=0$ no azeotrope would theoretically be formed because such azeotrope would boil at the same

70

temperature as the low boiling component. As the curve B shows, from the known data in regard to paraffins up to n-octane, it would be expected that when $|\Delta|$ reaches about 60°, little or no azeotrope formation would be obtained. This would cast serious doubt on the feasibility of using nitromethane for azeotroping paraffins boiling above 160° C. It has been found however that the $|\Delta|/\delta$ relationship in nitromethane-paraffin azeotropes is also anomalous in the higher boiling range. This may be seen by the inflection in curve B at about $|\Delta|=40$. Thus, at the point where $|\Delta|=73$, it is found that δ is about 2° thus permitting effective azeotroping in that range. Such effective azeotroping continues outwardly until $|\Delta|$ reaches about 120°. This means that nitromethane may be effectively employed for azeotroping paraffins and naphthalenes boiling up to about 220° C.

The advantageous relationship existing between nitromethane and higher paraffins does not accrue to the other nitroparaffins. The higher nitroparaffins are substantially more soluble in hydrocarbons and are hence less effective than nitromethane. Nitromethane moreover does not form azeotropes with aromatic hydrocarbons boiling above about 150° C., and hence there is no problem of fractionating azeotropes from each other, as there is in the case when toluene in admixture with low-boiling paraffins is azeotroped with nitromethane.

In actual operation the azeotropic separation is carried out in a conventional manner which is familiar to those skilled in the art. The crude hydrocarbons to be fractionated are simply distilled in a column along with the liquid nitromethane, and the low boiling azeotrope (boiling point 97-99° C.) is taken overhead and condensed. Upon condensation two liquid phases are formed, a lower solvent-rich phase and a supernatant paraffin-rich phase. The phases are then separated and separately topped in distillation columns to strip out any dissolved nitromethane or paraffin as azeotrope, and the resulting azeotropes are condensed and returned to the liquid-liquid phase separator to be further resolved. The stripped nitromethane is then returned to the primary azeotroping column, and the stripped paraffins or naphthalenes are recovered as bottoms from the paraffin stripping column. The C-9 aromatics which are removed as bottoms from the azeotroping column are recovered in approximately 99% purity and 99% yield.

The operation of this process in connection with a specific gasoline fraction may be more readily understood by referring to the drawing which is a flowsheet of one particular modification of the process. A stream of cracked or straight run gasoline, or a blend thereof, is brought in as feed through line 1, preheated in heat exchanger 2, in heat-exchange relationship with hot product gases in line 3, and transferred via line 4 to a heater 5. Recycle hydrogen is admitted to the gasoline stream through line 6 and the vaporous mixture of gasoline and hydrogen is heated in heater 5 to the desired reforming temperature e. g. 900-1200° F. The preheated mixture is then passed into catalytic reactor 7 wherein the hydrocarbons are subjected to reforming as described above. The conditions for reforming are conventional in the art and hence will not be described in detail. The catalyst in reactor 7 may comprise any of the known hydroforming catalysts e. g. platinum on an alumina or silica carrier, cobalt molybdate on a suitable carrier such as alumina, clay, bauxite, etc. Any of the oxides or sulfides of the transitional metals may be employed as catalyst, e. g. nickel, cobalt, tungsten, chromium, molybdenum, vanadium, iron, etc. The pressure in the reactor may vary between about 0 and 1000 p. s. i. g. The space velocity may be between about 0.2 and 10 volumes of liquid feed per volume of catalyst per hour. The recycle hydrogen may vary between about 1000 and 10,000 S. C. F. per barrel of feed.

The gaseous products from reactor 7 are withdrawn

through line 3, condensed in heat exchange relationship with the feed as previously described, and the liquid products are then transferred via line 9 to a gas-liquid separator 10. The noncondensable gases comprising hydrogen, methane, ethane, propane and small amounts of hydrogen sulfide, are withdrawn through line 11. Inasmuch as there is ordinarily a net make of hydrogen in the reactor, a part of the gas stream may be bled off through line 12 and utilized as fuel or for other purposes. The hydrogen for recycle is diverted through line 6 and returned to be admixed with fresh feed as previously described. In order to prevent the buildup of inert gases in the system, it may be desirable to bleed off a stream of recycle gas from line 6 and purify it by conventional means not shown in order to enrich the hydrogen gas which is actually recycled through heater 5.

The reformed gasoline in separator 10 is withdrawn through line 14 and transferred to a first fractionating column 15. In this column the low boiling fraction boiling below e. g. 160° is taken off as overhead through line 16, and the high boiling bottoms is transferred via line 17 to a second fractionating column 18. Column 18 is operated so as to take overhead through line 19 a cut boiling between about 160° and 170° C., and preferably between about 165° and 170° C. An even closer boiling cut boiling at 167-168° may be taken if desired. This overhead ordinarily comprises at least about 50% aromatics. If the feed material was high in naphthalenes the percent of aromatics in the overhead in line 19 may range up to 80-90%. Substantially all of the remaining hydrocarbons in the overhead are paraffins and naphthalenes with substantially no olefins. The bottoms from distillation column 18 is withdrawn through line 20 and comprises the higher boiling gasoline hydrocarbons which may be employed as blending stock or for any other desired purpose.

The aromatic stream in line 19 is next transferred to azeotropic distillation column 22. Recycle nitromethane is introduced through line 23. The azeotropic overhead from column 22 boils at about 96-99° C. and is taken off through line 24, condensed in condenser 25 and transferred via line 26 to liquid-liquid phase separator 27. The lower phase formed in separator 27 consists of nitromethane together with a small amount of dissolved hydrocarbons. This lower phase is taken off through line 28 and topped in column 30 to remove the hydrocarbons as azeotrope with part of the nitromethane. The azeotrope is removed overhead through line 31, condensed and recycled via line 32 to separator 27. The stripped nitromethane is removed as bottoms from column 30 through line 23, and recycled to azeotroping column 22 as previously described. The supernatant phase in separator 27 consists of paraffins and small amounts of naphthalenes, together with a small proportion of dissolved nitromethane. This mixture is taken off through line 33 and transferred to column 34 wherein the dissolved nitromethane is removed as azeotrope through line 35, condensed and recycled to separator 27. The bottoms from column 34 is taken off through line 36 and consists almost entirely of C-8, C-9, and C-10 paraffins which may be utilized for any desired purpose.

The bottoms from azeotroping column 22 is taken off through line 38, and consists of substantially pure C-9 aromatic hydrocarbons, mainly pseudocumene and mesitylene. This material may be utilized directly as raw material for various chemical syntheses involving for example nitration, oxidation, or the like.

The above described azeotroping system may obviously be modified in many of its details without departing from the essential scope of the invention. By adjusting the cut points in distillation columns 15 and 18 substantially any desired high boiling hydrocarbon fraction may be azeotroped in column 22 to obtain the corresponding higher boiling aromatics. The following example may

serve to illustrate more specifically the type of separations which may be obtained, but should not be interpreted as limiting the scope of the invention.

A sample of the reformate is then fractionated in a 20 plate column at a 10/1 reflux ratio. A heart-cut is taken off boiling between 167.1 and 168.2° C., which consists of 81% aromatic hydrocarbons and 19% paraffins plus naphthenes. The aromatic fraction is comprised of 51% pseudocumene and 11% mesitylene.

36.8 ml. of the above heart-cut is mixed with 31 ml. of nitromethane and the mixture is then subjected to azeotropic distillation, taking overhead the following cuts which are condensed to form two liquid phases:

Cut No.	Overhead Temperature, ° C.	Volume (ml.) of CH_3NO_2 hydrocarbon	Vol. percent non-aromatics in hydrocarbons
1	92	1.2	1.2
2	96	1.8	1.6
3	96-97	2.8	1.9
4	98	4.0	1.9
5	99	4.5	0.9
6	99	3.5	0.3
7	99.5	6.6	0.2

29.1 ml. of hydrocarbons are recovered in the bottoms, which are found to be 99+ percent aromatics. This represents a recovery of about 98-99% of the aromatic hydrocarbons initially present.

This example demonstrates the remarkable efficiency with which high boiling aromatics may be recovered from a predominantly aromatic heart-cut of reformate. In fact, no other known azeotrope former is capable of giving as efficient a separation.

The foregoing disclosure is not to be considered as limiting the scope of the invention since many variations may be made by those skilled in the art without departing from the scope or spirit of the following claims.

I claim:

1. A process for recovering an aromatic hydrocarbon fraction consisting mainly of pseudocumene and mesityl-

ene from catalytically reformed gasoline which comprises fractionating said gasoline to obtain a predominantly aromatic heart-cut boiling between about 165° and 170° C., subjecting said heart-cut to azeotropic distillation with 5 nitromethane, removing overhead an azeotrope of nitromethane and non-aromatic hydrocarbons, and recovering as bottoms a paraffin-free, naphthene-free aromatic hydrocarbon fraction which is predominantly pseudocumene and mesitylene.

10 2. A process for recovering C-9 alkaryl hydrocarbons from catalytically reformed gasoline which comprises fractionating said gasoline to obtain a predominantly aromatic fraction boiling between about 160° and 170° C., subjecting said fraction to azeotropic distillation with

15 nitromethane, removing overhead an azeotrope of nitromethane and non-aromatic hydrocarbons, and recovering as bottoms a paraffin-free, naphthene-free aromatic hydrocarbon fraction.

3. A process as defined in claim 2 including the steps 20 of condensing said azeotropic overhead to form a nitromethane-rich liquid phase and a hydrocarbon-rich liquid phase, separating said liquid phases, separately distilling said liquid phases to strip nitromethane azeotropically from said hydrocarbon phase and to strip hydrocarbons

25 from said nitromethane phase, and recovering substantially pure non-aromatic hydrocarbons and nitromethane as bottoms from said respective distillations.

Art C. McKinnis

It is hereby certified that error appears in the printed specification of the above numbered patent requiring correction and that the said Letters Patent should read as corrected below.

Column 1, line 49, for "reforming of" read—reforming or—; column 2, line 46, beginning with "It is well known in azeotropy", strike out the entire subject matter to and including "boiling up to about 220° C." in column 3, line 16; column 5, line 3, after "scope of the invention." insert the following—

EXAMPLE I

An aromatic reformate having a specific gravity of 0.81 is obtained by the hydroforming of a straight-run gasoline boiling at about 200°-500° F. in the presence of a platinum-alumina catalyst containing 0.5% by weight of impregnated platinum. The hydroforming conditions are as follows:

temperature..... 950° F.
pressure..... 100 p. s. i. g.
space velocity..... 1.0.
H₂, SCF/Bbl feed..... 5000.

column 5, lines 15 to 25, the third and fourth columns of the table should appear as shown below instead of as in the patent—

Volume (ml.) of	
CH ₃ NO ₂	Hydrocarbon
1.2	1.2
1.8	1.6
2.8	1.9
4.0	1.9
4.5	0.9
3.5	0.8
6.6	0.2

Signed and sealed this 28th day of October 1958.
